ELECTRICAL CONTROL CONSOLE

Paul V. De Luca, Port Washington, N.Y., assignor to
Porta Systems Corp., Port Washington, N.Y.

Filed June 9, 1970, Ser. No. 23,391

Term of patent 14 years

Int. Cl. D14—02

U.S. Cl. D26—5

FIG. 2

FIG. 1

FIG. 4

FIG. 3

FIG. 5

FIG. 1 is a perspective view of the electrical control console embodying my new design;

FIG. 2 is a side view of the electrical control depicted in FIG. 1;

FIG. 3 is a top view of the console depicted in FIG. 1;

FIG. 4 is a rear view of the console depicted in FIG. 1; and

FIG. 5 is an enlarged front view of the control panel of the console depicted in FIG. 1.

I claim:

The ornamental design for an electrical control console, substantially as shown.
